RECEIVER TUNING CONTROL

Dudley E. Foster, Orange, N. J., assignor to Radio Corporation of America, a corporation of Delaware

Application December 23, 1935, Serial No. 55,749

24 Claims. (Cl. 250—20)

My present invention relates to radio receiver tuners, and more particularly to novel and improved arrangements for accurately adjusting, in a simple manner, the tuning device of a radio receiver of the superheterodyne type.

In the past, radio receivers have been tuned by variation of the capacity of the receiving circuit through the medium of a reduction gear tuning knob. This has been necessary because of the high selectivity provided by modern broadcast receivers, and particularly receivers of the superheterodyne type. Moreover, the addition of automatic volume control to modern receivers has resulted in rendering the tuning comparatively difficult in spite of the reduction ratio of the mechanical drive between the tuning device and the manually adjustable tuning element. This is explained by the fact that the automatic volume control network tends to hold the signal level constant so that the listener has no ready means of determining exact resonance; except by the use of auxiliary devices. Accordingly, it will be seen that the reduction ratio tuning mechanism, necessitated by modern receiver selectivity, not only results in slow and tedious tuning operation, but also gives rise to inaccuracies in such tuning.

Automatic frequency control (AFC hereinafter) for a superheterodyne receiver has been previously known; this control tends to automatically center the received signal in the I. F. (intermediate frequency) reception band. However, the tuning operation is greatly simplified by the utilization of the AFC. Therefore, advantage may be taken of this fact to simplify the tuning mechanism for the purpose of obtaining ease and rapidity of tuning.

Accordingly, it may be stated that it is one of the primary objects of my present invention to take full advantage of the utilization of AFC in a receiver of the superheterodyne type, and to provide a manually adjustable tuning mechanism which enables the user rapidly to change the setting of the tuning device to any point required for reception of a desired signal.

Another important object of the invention is to provide an instantaneous selector device in mechanical association with the tuning condenser mechanism, and wherein the selector may be adjusted to positions corresponding to predetermined station settings of the tuning condenser; an AFC network in the receiver functioning to remove the necessity for mechanical accuracy imposed by modern receiver selectivity.

55 In practical operation the employment of the

AFC network gives rise to a so-called "carry over" difficulty. Since the AFC tends to keep the local oscillator frequency constant over an appreciable range of variation of the tuning condenser, if a signal is brought within the reception band the AFC functions to maintain the oscillator frequency such that this signal only gives the correct intermediate frequency. Hence, it will be seen that in tuning a receiver equipped with AFC, the station signal first operating the 10 control will be held after the tuning condenser position corresponding to an adjacent signal channel has been passed over. This "carry over" action, in brief, arises by virtue of the AFC causing a shift in the local oscillator frequency to 15 such an extent that one received carrier will continue the operation of the AFC to the exclusion of one or more adjacent carriers.

Further investigation connected with the embodiment of AFC in a superheterodyne receiver, 20 and the simplification of the tuning operation, has resulted in an altered conclusion with respect to the correlation of the tuning mechanism and the functioning of the AFC network. It has been found that in order definitely to ensure reception of desired stations, the AFC must be rendered inoperative during the portion of the tuning operation just prior to the tuning condenser setting at which the desired signal would be obtained with the AFC in inoperative condition. 30 When, however, the variable condenser has been adjusted within the channel of the desired station, the AFC is again rendered operative and completes the tuning operation. Such a correlation of AFC operation and tuning adjustment, 35 not only results in a complete simplification of the tuning operation, and accuracy of station selecting, but further gives rise to "quiet" tuning between adjacent signal channels where automatic volume control is utilized.

It may, therefore, be stated that it is another important object of my present invention to provide in a superheterodyne receiver equipped with AFC and a station selector dial mechanism which is mechanically coupled with the tuning condenser device, a control switch located at a fixed reference point with respect to the selector dial, and which functions to render inoperative the AFC during a relatively small portion of the dial rotation in order to eliminate the tendency of 50 the AFC to cause a shift in the local oscillator frequency to an extent that one carrier will cause response to the exclusion of other carriers.

Still another object of my present invention is to provide a simplified and accurate station se- 55

lector device for a radio receiver of the superheterodyne type, and which receiver is equipped with AFC of the local oscillator; the station selector generically comprising a rotatable dial 5 provided with a series of spaced openings; the openings corresponding to different desired stations; and a shiftable stop element being positioned in such relation with respect to the selector dial that the receiver tuning device has 10 its motion of adjustment arrested at the same location regardless of whether the rotation of the dial is clockwise or counter-clockwise.

Another object of this invention is to provide a radio receiver of the superheterodyne type with 15 an AFC network, as well as a station selector dial for simply and accurately adjusting the tuning condensers of the receiver; the dial being provided with adjustable spaced station buttons provided with elements adapted to mechanically 20 operate with a dial rotation stop member in order to limit the rotation of the dial in accordance with selected station buttons; and the selector dial being further associated with a control member for the AFC network with the result that 25 the AFC is operative at all times except when a selected button is adjusted into mechanical cooperation with the stop mechanism.

And still other objects of my present invention are to improve generally, the simplicity, accuracy 30 and efficiency of the radio receiver tuning control mechanism, and more especially to provide such mechanisms in superheterodyne receivers equipped with AFC, and which mechanisms may be embodied in the receivers in an economical 35 and easy manner.

The novel features which I believe to be characteristic of my invention are set forth in particularity in the appended claims, the invention, itself, however, as to both its organization and 40 method of operation will best be understood by reference to the following description taken in connection with the drawings, in which I have indicated various mechanical embodiments whereby my invention may be carried into effect.

45 In the drawings:

Fig. 1 schematically shows a superheterodyne receiving system embodying one form of the invention.

Fig. 2 is a front view of the station selector mechanism, of the type shown in Fig. 1, as viewed 50 from the front of the radio receiver operating panel.

Fig. 3 is a partial sectional view of the station selector mechanism, taken along line 3-3 of Fig. 55 2 looking in the direction of the arrows.

Fig. 4 is a detailed view of the AFC switch when in "on" position.

Fig. 5 is a view of the switch of Fig. 4 in "off" position.

Fig. 6 is a front view of a modified form of 60 station selector mechanism.

Fig. 7 is an end view, partly in section, of the detailed construction of the modification of Fig. 6.

Fig. 8 is an end view of the selector modification in Fig. 6.

Fig. 9 is a front view of still another modified form of selector mechanism.

Fig. 10 is an end view, partly in section, of the 70 selector modification of Fig. 9.

Fig. 11 is another modification, viewed from the receiver panel, of the type of selector mechanism shown in Fig. 9.

Fig. 12 is an end view, partly in section, of the 75 modification shown in Fig. 11.

Referring now to the accompanying drawings, wherein like reference characters in the different figures designate similar constructional elements, attention is first directed to Fig. 1 which shows in purely schematic manner a superheterodyne 5 receiver embodying AFC, as well as a simplified and accurate manual tuning mechanism. Since the functioning of the present invention is not dependent in any way upon the particular construction of the superheterodyne receiver, or the specific AFC network employed therewith, it is believed sufficient for the purposes of this application to point out a typical receiving system which can be utilized in conjunction with the novel station selector mechanism of my present 10 invention. The receiving system shown in Fig. 1 is a conventional representation of the system shown in detail in Fig. 4 of application Serial No. 45,413, filed October 17, 1935 by S. W. Seeley, patented June 21, 1938 as U. S. P. 2,121,103. 15

It will be sufficient for those skilled in the art, to briefly describe the main elements of such a superheterodyne receiving system which is provided with AFC. The usual signal carrier energy 20 collector A, such as a grounded antenna; a radio frequency distribution line; or the conventional collector used on an automobile radio receiver; is coupled to the tunable input circuit of the receiver. The tunable input circuit usually 25 comprises a variable tuning condenser 1, and it is to be clearly understood that the first stage of the receiver may be a radio frequency amplifier. In order to preserve simplicity of disclosure and drawing, the numeral 2 designates 30 the first detector.

The output circuit 3 of the first detector is 35 resonated to the operating intermediate frequency, which may have a value, for example, of 175 to 465 k. c. (kilocycles). The I. F. amplifier 4 has its input circuit 5 resonated to the operating I. F. and coupled to the first detector output circuit 3. The I. F. amplifier 4 is followed by a double diode tube, as in the 6H6 type tube. 40 This type of tube is provided with independent diode electrodes, and the common resonant input circuit 7 has one side thereof connected to the diode anode 8, while the opposite side of the circuit is connected to the diode anode 9. The high alternating potential side of the output circuit 6 of the I. F. amplifier 4 is connected through condenser 10 to the midpoint of the coil 7' of 45 input circuit 7. This midpoint 11 is connected to the junction of resistor portions 12 and 13; one side of resistor 12 being connected to the cathode 8' of the diode 8-8', and one side of resistor 13 being connected to the cathode 9' of the diode 9-9'. 50

The condenser 14 is connected between cathodes 8' and 9', and the cathode 9' is grounded. 55 The input circuit 7 is tuned to the operating I. F., and is reactively coupled to the circuit 6, as designated by the reference letter M. The audio component of detected I. F. energy is impressed upon one or more audio amplifier stages, followed by a reproducer, through lead 15 and condenser 16, the latter being connected to the junction of resistors 12 and 13. The automatic volume control (AVC) connection 17 is employed to apply the direct current voltage component of rectified I. F. energy to the signal grids of controlled tubes 2 and 4. The AVC connection 17 is made to the junction of resistors 12 and 13, and of course, the direct current voltage component is transmitted through appropriate filter resistors before being 70 75

applied to the gain control grids of the controlled tubes.

The AFC network involves the tunable tank circuit 18 of the local oscillator 19. As is well known the variable condenser 20 in the tank circuit 18 has its rotors mechanically uni-controlled with the rotors of the variable tuning condensers of the tunable signal circuits feeding the first detector. The dotted line 21 represents such mechanical uni-control. Of course, the oscillator 19 is tuned, at any setting of the tuning mechanism 21, to a frequency which differs from the frequency of the signal circuits by the operating I. F. Those skilled in the art are fully aware of the manner of employing padding condensers in the tank circuit 18 for maintaining the operating I. F. constant in value as the tuner 21 is varied through the operating frequency range, which may be the broadcast band of 500 to 1500 k. c.

The locally produced oscillations are impressed on the first detector 2 in any desired manner, as by impressing them on the cathode circuit of the first detector. Of course, it is not essential to this invention to employ separate tubes 2 and 19 for the mixer and oscillator functions. A pentagrid converter of the 2A7 type may be employed, in any well known manner, for a composite oscillator-mixer stage. In any case there is electrically associated with the tank circuit 18 a frequency control tube 22. The connections between the plate circuit of tube 22 and tank circuit 18 are such that a negative capacity is reflected across the tank circuit.

Briefly, and without going into a detailed discussion of the specific connections between the frequency control 22 and the tank circuit 18, it is pointed out that a resistor 23 and condenser 24 are connected in series across the tank circuit 18. If the resistance of resistor 23 is large compared to the reactance of condenser 24, currents through this series circuit will be substantially in phase with the voltage across the tank circuit 18.

The current passing through the condenser 24 produces a voltage across the condenser which lags the voltage across the tank circuit by substantially 90°. This lagging voltage is applied to the grid of control tube 22, and the latter is preferably of the high mu, high plate impedance type. It can then be seen that the plate current, flowing in connection 25 to tube 22 will be substantially 90° ahead of the voltage across the tank circuit 18. The current through the tuning condenser of the tank circuit 18 lags the voltage across that circuit about 90°. Thus, any plate current flowing through connection 25 to tube 22 acts as though the current flowing in the variable tuning condenser has been decreased.

The AFC connection 26 is made from the control grid of tube 22, through an appropriate filter resistor, to the cathode side of resistor 12. The mutual conductance of tube 22 is varied in dependence upon the magnitude of the direct current component of the differential rectified I. F. energy. The magnitude and polarity of the potential at the cathode side of resistor 12 determines the sense of magnitude variation of the effective inductance reflected across tank circuit 18 by control tube 22.

The AFC action is secured by virtue of the fact that when the primary and secondary voltages of a double tuned transformer, which voltages differ 90° in phase when energy of the resonant frequency is applied, are added vectorially, the absolute magnitude of the resultant

vector will be greater on one side of resonance than on the other. In the type of discriminator network shown in Fig. 1, the primary and secondary circuits 6 and 7 are so related that two vector sum potentials of the primary and secondary voltages may be realized. The magnitude and the polarity of the potential at point 40 determines the magnitude of the effective inductance reflected across tank circuit 18. Thus, if the AFC voltage applied to the grid of tube 22 is positive (thereby overcoming some of the initial bias applied in the cathode circuit of that tube), its mutual conductance is increased. The amount of leading current flowing in connection 25 is thereby increased; which is the same as through the lagging current flowing through the variable tuning condenser 20 has been decreased. This, in turn, acts as though that condenser had been decreased in value thereby causing the tuned frequency of tank circuit 18 to increase.

Assume, now, that a signal impressed on primary circuit is approaching the I. F. value of 465 k. c., an operating frequency chosen by way of illustration, but is less than the latter; and also assume that point 40 has a positive potential with respect to ground. Then the frequency departure may be due to a shift in oscillator frequency towards a lower frequency, or due to tuning the receiver towards the high end of the tuning range. The grid of tube 22 becomes positive, and increases the gain of the tube. This will result in an increase in the effective inductance reflected across tank circuit 18; and the frequency of the tank circuit will increase. In this way the frequency difference between the signal and oscillator circuits automatically is made to increase towards the desired I. F. value.

A practical difficulty encountered in employing AFC in a superheterodyne receiver is the problem of dislodging a strong signal to make way for a weaker one on a closely adjacent channel, without having the weaker station jump right across the band to disappear on the other side. To overcome this difficulty a switch 30 may be employed.

The switch 30 functions to ground the bias voltage derived from point 40, and renders the AFC network inoperative at the will of the operator. This offers a means for correlating the operation of the AFC network with the tuning operation so as to render the tuning of the receiving system not only accurate, but highly simplified. In Fig. 1 there is shown schematically such a simplified type of tuning mechanism. The switch 30 is supplemented by an auxiliary switch 31 which comprises a relatively fixed contact element 32, and a relatively movable contact element 33. The contact 32 is connected by lead 34 to the AFC line 26, whereas the contact 33 is grounded. In actual practice the switch 30 may be mounted in the rear of the receiver chassis, whereas the supplementary switch 31 may be mechanically associated with the selector dial as shown in Fig. 3.

The station selector mechanism that is employed is of the dial type. It generally comprises a rotatable disc 40 which is provided with a plurality of station selector elements, or ears, 41. Each of these elements 41 is provided at its outer end with a depressible button 42; and at its inner end with a threaded screw member 43. The function of members 43 is to adjust each of the selector elements 41 in any desired radial position along the periphery of the dial disc 40. A groove 44 in the exposed face of the dial disc 40

is provided for cooperation with the ends of adjusting screws 43. This permits the elements 41 to be adjusted to different points along the periphery of disc 40. Upon depression of a button 42, a pin 45 is projected to the rear of the disc 40. The projected pin 45 has a path of revolution such that it comes in contact with the end of a pivoted switch closure member 46, the latter being limited in pivotable motion between a pair of stops 47. The upper end of switch closure member 46 is provided with a widened edge, one point of which is capable of moving the contact element 33 into circuit "off" position when the pin 45 is moved into abutting position against the member 46.

When the disc 40 is rotated in one direction the pin 45 associated with a particular depressed button 42 will move the closure member 46 in the direction of rotation of the disc. When the latter is rotated in the opposite sense, then a pin 45 will move the member 46 in the opposite direction. However, regardless of the sense of rotation of disc 40, the pin 45, when shifted into contact with closure member 46, will result in grounding of the AFC line 26 through the path including lead 34; contact elements 32 and 33 and ground. The disc 40 may be coupled mechanically to the uni-control adjusting means 21 through any desired mechanical coupling arrangement. For example, a 2 to 1 reduction gear ratio is shown employed to mechanically couple the tuning device 21 to the rotatable disc 40. This reduction gearing comprises a small drive gear 46 which is rotated in unison with disc 40; the driven gear 47 meshing with gear 46, and in turn having a rigid connection to the tuning element 21.

In general, therefore, it will be seen that the manually adjustable tuning device of the receiving system comprises a rotatable station selector disc provided with a plurality of independent station selecting buttons 42. The tuning process involves the insertion of the user's finger in the bore housing a button 42, assuming the button has been depressed, and the rotation of the dial 40 with its plurality of carrier members 41. The rotation ceases when the particular pin 45 moves into contact with the pivotable closure member 46, and the latter moves into contact with one of the stop pins 47. This results in the rendering of the AFC inoperative at that point, as well as a positive arresting of the rotation of dial 48. The button 42 is released thereby withdrawing pin 45, and opening switch 31.

The constructional details of the selector dial and its plurality of button carrier members will now be considered. Particular attention is directed to Figs. 2 to 5 inclusive for these constructional details. In Fig. 2 there is shown the appearance of the station selector mechanism when viewed from the front of the operating panel of a radio receiver. The disc 40 is provided, concentrically therewith, with an annular dial bearing scale indicia 51 which denote the various frequencies to be received. Where the receiver is of the multi-range type, this circular dial 50 will bear a plurality of scale ranges to correspond to the different frequency bands of the receiver. The scale 50 is rigidly secured to the outer face of disc 40 in any desired manner; rotation of the disc 40 therefore also resulting in rotation of the dial 50.

Each of the button carrier members 41 is bifurcated at the point of contact with the periphery of disc 40. As shown in Fig. 3 in greater

detail, each of the members 41 is rigidly secured to a predetermined position on the periphery of disc 40 by means of the threaded coupling between screw 43 and the threaded bore provided in one of the legs 51' of the bifurcated portion of each of members 41. Each of screws 43 is provided with a ball tip 52, the tip being shaped to complement the shape of the groove 44. That is to say, the cross section of groove 44 will be substantially semi-circular so as to receive snugly the semi-circular contour of the ball tip 52. It will now be seen that a member 41 can be substantially rigidly secured to the periphery of disc 40 by the use of a screw driver, which is employed to rotate the desired screw 43. The buttons 42 are disposed within bores provided at the free ends of each carrier member 41.

As shown in Fig. 3 a button 42 comprises a shank 60 which is adapted to reciprocate through a narrow bore provided at the rear face of the member 41. This rear bore widens into a second bore adapted to receive a spring 61 which normally maintains the head 62 of a button in a position such that the exposed face of the head 62 is substantially in the same plane with the remainder of the exposed face of member 41. The head 62 of each button is arranged to reciprocate within a third and wider bore 63. The head 62 may comprise, as shown in Fig. 3, a comparatively narrow recessed casing within which is disposed a circular station designation plate 64 having its upper face in contact with a transparent protective circular plate 65. As shown in Fig. 2, the head of each button will, therefore, have exposed to the view of the set user the various station call letters. Those shown in Fig. 2 represent the various station call letters of broadcast stations encountered in the New York City area.

The shank 60 of each button device 42 is provided with a normally protruding pin 70. The portion of the pin 70 between shank 60 and the rear tip of the pin is in threaded engagement with a nut 71. The latter nut functions as a stop nut, and its face, in contact with the rear face of ear 41, limits the movement of pin 70 in the direction of the operating panel. Upon movement of the button head 62 in a direction to compress spring 61, it will be seen that the pin 70 is moved into alignment with the path of movement of the double bell crank lever switch 46 which functions to close the AFC control switch 31. Upon removing the depressing force from the button head 62, the spring 61 pushes the head 62 into its normal position, and thus retracts the pin 70 from the path of the lever 46.

The AFC switch 31, as shown in detail in Figs. 4 and 5, comprises the contact elements 32 and 33. The element 32, as well as element 33, has one end thereof positively gripped between insulation spacers 72. The contact element 33 has spaced therefrom a presser strip 73, one end of which is also gripped between insulation spacers. The bolts 74 function to rigidly secure together the various insulation spacers, and maintain the ends of strips 32, 33 and 73 in spaced relation. The fixed ends of contact elements 32 and 33 project beyond the spacers 72, and numerals 75 and 76 designate these projecting ends which act as connecting terminals to the lead 34 and ground. The free end of element 32 is provided with a button 77, and the free end of contact element 33 is provided with a contact pin 78.

Since the strip 32 is in metallic engagement with the button 77, and the same is true of element 33 and its pin 78, contact between elements 77 and 78 results in a closing of the circuit from lead 34 to ground. This occurs when the presser strip 73 is urged towards contact element 33; the strip 33 is provided with an insulation spacer 79 which is normally in contact with element 33. Normally the upper edge 10 of the member 46 is in contact with the lower face of strip 73. Member 46 is pivoted, as at 81, and has a depending portion 46' which is arranged to swing between the stop pins 47, 47'. In Fig. 5 is shown the two limiting positions of the member 46, the dotted line position of member 46 showing its relation to the switch elements when it is moved into contact with pin 47. The full line position of member 46 in Fig. 5 shows its relation to switch 31, when the depending 20 portion 46' is moved into contact with stop 47'.

The upper edge 80 of member 46 is moved out of contact with the under surface of presser strip 73 whenever the depending portion 46' is swung towards either of the stops 47 or 47'. It will also 25 be seen that regardless of the direction of movement of the depending portion 46', the contact elements 32 and 33 will be brought into electrical association by the front and rear cam edges of the upper portion of member 46. Of course, 30 the elements 32, 33 and 73 are made of flexible metallic strips so that when the cam edges of edge 80 are moved along the under face of strip 73, the three spaced strips will be capable of yielding in the direction in which they are urged.

35 The bolt 81, which acts as the pivot point for member 46, is rigidly secured to a support plate 82, the latter being spaced from the operating panel 83 of the receiver. As shown in Fig. 3, the front panel 83 of the receiver is provided 40 with a metallic ring 84. The disc 40 is disposed concentrically with respect to the ring 84, and as seen in Fig. 2, the ring 84 serves as an outer setting for the disc and button carrier assembly. It will be observed that there is a substantial 45 peripheral space between the periphery of the circle of revolution of the button carriers, and the inner circular edge of ring 84. The spaced plate 82 has secured to it, at a short distance from its upper edge, the bolt 81. The stops 47 and 47' 50 are secured to the front face of plate 82, the stops being spaced from each other in the manner shown in Fig. 4. The depending portion 46' of member 46 has its rear face in contact with the front face of plate 82, so that when member 46 55 is shifted between the stops 47 and 47', its rear face is in sliding contact with the front face of plate 82.

The plate 82 is rigidly secured to the chassis of the receiver in any desired manner, and through 60 the center thereof there is provided an aperture which acts as a bearing for the shaft 85, which is integral with the rotor condenser shaft 86. The gear 87 is secured to the end of shaft 85 in any conventional manner, and gear 87 meshes with 65 driving gear 88. The gear 88 is pinned to the integral hub 89 of disc 40. The hub 89 is provided with a tubular extension 90, the latter extending to the rear of hub 89, and through a second aperture in plate 82. The extension 90 and hub 89 is 70 provided with a bore in which is disposed the horizontal portion 91 of the fixed index arm 92. As clearly shown in Fig. 3, the index arm 92 is formed from a single element, the vertical exposed index arm 92 being maintained in the same 75 fixed position by virtue of a downwardly directed

bent portion 93, which is secured to the rear face of plate 82 in any conventional manner.

The shaft 86 of the uni-controlled gang of condensers is additionally coupled, if desired, to a conventional form of tuning knob 94. As clearly 5 shown in Fig. 3, the tuning knob 94 may be provided in the lowermost portion of circular ring 84, and in alignment with the index arm 92. A shaft 95 is provided, which may be arranged parallel 10 to condenser shaft 86, and this shaft had an end thereof which has the knob 94 secured thereto. The manually rotatable shaft 95 can be mechanically coupled to condenser shaft 86 in any conventional fashion; a belt and pulley arrangement 96 being shown by way of example. It is 15 to be clearly understood, however, that the tuning knob 94 and its associated mechanical coupling to condenser shaft 86, may be entirely omitted; since it is only necessary to use the station selector dial 40.

The numeral 97 designates the variable tuning condenser element of the radio receiver. It is not believed necessary to describe the construction of this element since those skilled in the art are fully aware of such construction. It is only 20 believed necessary to point out that the numeral 97 denotes the conventional gang of variable condensers corresponding to the variable tuning condensers 20 and 1 of Fig. 1. It is also pointed out that gears 87 and 88 of Fig. 3 correspond respectively to gears 47 and 46 of Fig. 1. It will now be seen that as a button 42 is depressed, and the dial assembly 40 is rotated, the condenser shaft 86 will be rotated by virtue of the gearing 88—87. Since the index on 92 is rigidly anchored with respect to the rotating dial face 50, there is supplied, in addition to the station designations on the button faces, kilocycle designations to denote the position of condenser shaft 86 at any setting of the manually adjustable tuner device. 35

40 Regardless of the setting of the selector dial 40, excepting when the rotors of condenser 97 are fully in mesh with the stators or fully out of mesh therewith, it is possible to rotate the selector dial 40 in clockwise or counter-clockwise direction. Due to the construction of conventional variable tuning condensers, the condenser shaft 86 cannot be continued in adjustment in the same direction after being adjusted into complete meshing with the stators; neither can the rotor shaft be continued in adjustment in the same direction after the rotors have been rotated completely out of mesh with the stators. However, 45 between these two limiting positions, the rotor shaft 86 can be adjusted in clockwise or counter-clockwise sense. As is well known, this adjustment between the limiting positions is only through 180°. Hence a 2 to 1 reduction ratio gearing is used between shaft 86 and dial 40 to 50 secure advantage of 360° on the dial 40.

55 It is a very simple matter to initially calibrate the selector dial 40; or for that matter to service the AFC network and associated selector mechanism even when the receiver has been in the user's home for a long period of time. Whether 60 it is desired to initially calibrate the selector mechanism, or whether it is desired to re-calibrate the selector mechanism when a receiver is moved from one broadcast area into a relatively distant area, it is only necessary to rotate the 65 condenser shaft 86 by moving the dial 40 until a station is heard without appreciable distortion. At that setting of the condenser shaft 86 a button carrier member 41 is shifted along the periphery of dial 40 until pin 70 contacts portion 46' of 70 75

member 46, and moves the latter against one of the stops 47 or 47'. At that position of member 41, its screw 43 is tightened to fix member 41 to the dial 40 at the switch 31 closing position.

5. This procedure may then be repeated for as many of the remaining carrier members 41 as is desired. Of course, the calibration may be accomplished by employing the tuning knob 94, where one is provided on the receiver. If the 10 receiver is of the multi-range type, and the station selector dial 40 is used for the broadcast band exclusively, then it will be desirable to provide the tuning knob 94 for operation in the shorter wave bands. As stated before, the entire 15 360° of the selector dial 40 is utilized by virtue of the reduction gearing 88-87; this permits a wider distribution of members 41 on the selector dial.

The two members 31 and 46 definitely assure 20 reception of a desired station by causing the AFC to be rendered inoperative. This is accomplished during the portion of the tuning operation just prior to the tuning condenser setting at which the desired signal would be obtained with the 25 AFC in inoperative condition. When the variable condenser rotation is such that the condenser shaft 86 has adjusted the rotors of condenser 97 to tune the oscillator and signal circuits within the channel of the desired station, 30 then the AFC is again rendered operative and completes the tuning operation accurately. Considered in mechanical procedure, this electrical sequence of tuning steps is accomplished in the following manner.

35 Assuming that station WINS is being received, as shown in Fig. 2, and it is desired to tune the receiver to station WEAF, it is only necessary to insert a finger into the carrier member 41 provided with the WEAF button. This is accomplished by pressing down on the WEAF button. The entire selector dial assembly is then rotated in clockwise, or counter-clockwise, direction depending on the position of the condenser rotors.

There will be no obstruction to the movement 45 of the WINS button because its pin 70 is in retracted position. The projected pin 70 of the WEAF button will cause rotation of dial 40 to cease as soon as the pin strikes the depending portion 46' of member 46, and causes portion 46' 50 to abut one of the stop pins 47 or 47'. When the user of the set observes that further movement of the dial 40 is impossible, then it is merely necessary to remove the finger from the WEAF button. Removal of the pin 70 of the WEAF button 55 permits the member 46 to attain its position shown in Fig. 4, thus opening the switch 30 and restoring operation of the AFC. When the AFC becomes operative, it immediately functions to adjust the local oscillator frequency so as to accurately tune the receiver to WEAF. It will, 60 therefore, be seen that the initial calibration of the selector dial need not be very accurate. The action of the AFC is such that it will automatically and accurately tune the receiver after the receiver has been approximately tuned by adjustment manually of condenser shaft 86.

Of course, the station indicia on each button 42 may be made of material which glows in the dark, such materials being well known; thereby 70 facilitating adjustment of the dial in the darkness, as in the case of an automobile radio receiver employed in night driving. Again, the station indicia may be in braille so that blind persons may easily use the mechanism.

75 The switch 30, also controlling the AFC net-

work, may be used when it is desired to render the AFC inoperative for a long period of time, and independently of the switch 31. Again, it is to be noted that while the resiliency of strips 73, 33 and 32 can be relied on to restore the member 46 to its normal position shown in Fig. 4, it is obvious that the portion 46' may be designed to normally maintain the member 46 in its median position. While the dial 40 can be positioned on the operating panel above the tuning knob, tone 10 control knob and volume control knob, it is within the scope of my invention to dispose the selector dial at the side of the cabinet for aesthetic reasons. Again, if it is desired to keep the selector dial on the front panel, and if for design 15 purposes it is desired to keep the dial normally hidden from view, a slideable, or pivotable, door may be used to cover the selector dial. From Fig. 2 it will be seen that there is plenty of space between members 41 on dial 40 to provide for re- 20 calibration when the receiver is moved from one broadcasting area to an area where entirely different stations are broadcasting.

It is believed that the electrical operation of the AFC, as the receiver is tuned, will be obvious from 25 the foregoing description. As soon as the receiver is tuned within a desired signal channel, the AFC will immediately function to adjust the oscillator frequency so as to produce I. F. energy substantially equal to the operating I. F. Because of this functioning of the AFC network, an additional advantage is secured by virtue of the selector dial construction. Since the receiver is equipped with an AVC network it functions to reduce the sensitivity of the signal selector 35 circuits as long as signal energy is applied to the AVC rectifier.

Since the AFC network is operative at all times in a receiving system embodying the present invention, it necessarily follows that signal energy 40 will be impressed on the AVC rectifier at all times. In other words, the AVC connection 17 in Fig. 1 is practically functioning at all times to reduce the sensitivity of the signal stages preceding the I. F. network. This is particularly 45 true when tuning from one station position of the selector dial 40 to another position. Whereas in a conventional radio receiver equipped with AVC, inter-station adjustment of the receiver results in much noise; the present receiving system and its station selector mechanism produces "quiet" tuning between channels. Further, it will be seen that this is accomplished without the use of any auxiliary, and well known types of, noise suppressor networks. In other words, 55 the AFC network not only functions to render the tuning operation simple and accurate; but it also cooperates with the AVC network to provide quiet interchannel operation.

A modification of the selector mechanism is 60 illustrated in Fig. 6. This latter figure shows the appearance of the selector mechanism as viewed from the operating panel. It will be seen that it comprises a disc 100 provided on its outer face with a plurality of spaced tubular devices 101. The outer face of disc 100 is also provided with a concentric scale disc 102, a stationary scale arm 103 depending from the rear of the operating panel 104, and cooperating with the indicia 105 provided on the disc 102. In Fig. 7 there is 70 shown in detail the manner of constructing one of the tubular finger positioning devices 101. It will be observed that each of the devices 101 comprises a cylindrical casing 106 having a base 107.

The base 107 is rigidly affixed to a desired point adjacent the peripheral edge of disc 100 by means of a tapped screw 108. The base 107 is provided with an L-shaped gripping hook 109 which grips the peripheral edge of disc 100. Each of casings 106 is provided with a rounded periphery at the exposed opening 110, and a false bottom disc 111 is provided at an intermediate point along the length of casing 106. The disc 111 bears on its outer face station indicia, and the latter are clearly shown in Fig. 6. The disc 100 is directly coupled to the condenser shaft 112. The numeral 113 designates, in Fig. 8, the gang of condensers, and it will be observed that the rotor shaft 112 is directly coupled to the disc 100 by any well known form of mechanical coupling 114. In view of this construction the finger positioning devices 101 can only be arranged along 180° of the exposed face of disc 100; this follows from the fact that the rotors of the variable condenser 113 can only be rotated through 180°.

The finger positioning devices 101 are arranged along the peripheral edge of disc 100 in the manner described previously in connection with the selector device shown in Fig. 2. The AFC switch is of a substantially similar construction, but differs from the type previously described in that a finger positioned in a device 101 directly operates the AFC switch. The switch comprises an elongated contactor 114 which is centrally pivoted to a support lug 115 by means of a pin 116. The support lug 115 is secured to the bottom of a support plate 117, the latter being spaced from, and positioned rearwardly of, the disc 100. The circuit closing end of contactor 114 is resiliently secured to a bracket 118 which depends from the lug 115. This is accomplished by securing spring 119 between the free end of bracket 118 and the contacting end of the contactor 114.

The spring-retained end of contactor 114 is provided with opposed contact points 120 and 121; and these points are arranged to cooperate with contacts 120' and 121' respectively. The latter two contacts are connected in common, and are provided with a single connection to the AFC network. The ground connection is provided to the contactor 114, and a pair of stops 122 and 123 are provided on either side of the contactor 114 in order to limit the arcuate motion thereof. The upper end of the contactor 114 is provided with a configuration as shown in Fig. 6, and it will be observed that this configuration generally comprises a pair of opposed concave arcs. The purpose of this configuration is to adapt the upper opposed edges of the free end of contactor 114 to the contour of a finger positioned in a device 101.

It will now be seen that a finger, disposed in a given cylinder 101, shifts the contactor 114 into AFC circuit closing position when the finger contacts the upper edge of the contactor and rotation of disc 100 is continued. As shown in Fig. 6, and assuming that WABC is desired for reception, it will be seen that the finger of the user will shift the contactor 114 into the dotted line position 114'. In this position, the stop 123 limits further motion of the contactor, and causes electrical contact between point 121 and contact 121'. In this position, the AFC network is inoperative, and normal tuning is permitted. As soon as the finger of the user is removed from the WABC cylinder, the spring 119 retracts the contactor 114 into normal position, and the AFC

network is operative to accurately tune the receiver.

In designing the stop device for the selector dial, whether it be for the form shown in Fig. 3, or the form shown in Fig. 6, it is necessary to have the pivotable switch closure member shifting in accordance with the direction of rotation of the selector dial. This assures the tuning means coming to rest in the same location regardless of whether the direction of rotation is clockwise or counter-clockwise. Mechanically, this action is secured by permitting the toggle member to be displaced from its normal, or center, position a distance equal to the radius of the toggle actuating means; in Fig. 3, this actuating means is a pin projected by a depressed button. Here, the abovementioned radius is the radius of the button pin. In the finger-actuated modification, this radius is that of the finger-positioning aperture.

The selector mechanism is shown in still further simplified form in Figs. 9 and 10. In this arrangement, the selector mechanism comprises a disc 130 having a bore 131, the bore receiving the rotor shaft 132 of the gang of condensers. In other words, the disc 130 is directly coupled to the rotor shaft. A semi-circular slot 133 is provided in the body of disc 130, thus providing a rear segment 134 and a front segment 135. The front, or selector, segment 135 is provided with a plurality of spaced openings 136, and the inner face of the rear segment 134 is provided with a station designation disc 137. The station indicia 137' are provided adjacent the peripheral edge of plate 137; the indicia being provided at points such that they can be viewed through their corresponding selector openings 136. As shown in Fig. 9, each opening 136 will then surround a corresponding station designation 137'.

Of course, the diameter of each opening 136 should be such that the finger size of the average set user can be accommodated. It is also to be understood that the AFC switch construction in connection with Figs. 6, 7 and 8 is to be employed in connection with this selector modification. The association of the form shown in Fig. 9 with an AFC switch is not shown because it is believed that those skilled in the art will readily appreciate the manner of this mechanical association from Figs. 6, 7 and 8.

It will be observed that in the last two modifications described, the station selector devices are limited to an 180° distribution along the periphery of the station selector disc. The entire circumference of the selector disc may be used by providing an additional AFC switch diametrically opposite to that shown in Fig. 6.

This form of selector mechanism is shown in Figs. 11 and 12. The selector disc and finger positioning devices are similar in construction to the form shown in Figs. 9 and 10. That is to say, the numeral 140 designates a selector disc provided with spaced finger positioning openings 141 around its entire periphery. The rear disc portion 142 is provided with the station indicia disc 143, and the indicia are arranged along the periphery of the latter so as to be readily viewed through the different openings 141.

One AFC switch 150 is located adjacent the lowermost point of disc 140, and a second AFC switch 151 is positioned diametrically opposite switch 150. It is to be clearly understood that both these switches are constructed as shown in Figs. 6 and 8. For this reason, these switches are schematically represented in Figs. 11 and 12.

The common connection to ground from the contacts of switches 150 and 151 is shown in Fig. 11, and the latter additionally shows the common connections from the pairs of contacts of each of switches 150 and 151 to the AFC network.

In this way, it is possible to use either of the modifications shown in Figs. 8 and 9, and yet have a wider distribution of finger positioning devices along the periphery of the selector disc. This can be easily seen from the fact that since the rotors of the variable condenser, to which shaft 132 in Fig. 12 is connected, have a maximum rotation of 180°, it is only necessary to position half the stations on half the disc 140, and the other half of the stations along the periphery of the other half of the disc. Because of this arrangement, and the provision of a pair of switches 150 and 151, regardless of the position of the rotors of the variable condenser, the maximum rotation of disc 140 will not exceed 180°.

It is thereby possible to have the spacing between finger position openings 141 much wider than in the modifications of Figs. 6 and 9; further, the advantage over the modification shown in Fig. 1 resides in the fact that no mechanical gearing is employed between the selector mechanism and the rotor shaft 132 and yet the full 360° of the selector disc is taken advantage of. An additional advantage of the modification shown in Figs. 11 and 12 over that shown in Fig. 1 resides in the fact that to adjust the rotor shaft 132 to any desired station setting from any last setting, the disc 140 need not be adjusted through an angular distance greater than 180°. In order to distinguish the stations on half of the disc 140 from the stations on the other half, a differential coloring can be employed on the station indicia.

40 While I have indicated and described several constructions for carrying my invention into effect, it will be apparent to one skilled in the art that my invention is by no means limited to the particular constructions shown and described, 45 but that many modifications may be made without departing from the scope of my invention, as set forth in the appended claims.

What I claim is:

50 1. In combination with the adjustable tuning device of a radio receiver, supplemental means for tuning the receiver, a device for controlling the operation of the supplemental means, a rotatable station selector disc arranged to vary said tuning device to different station reception positions, a plurality of independent finger positioning devices mechanically associated with said disc, and means, relatively fixed with respect to said rotatable disc, for stopping the rotation of said disc, and actuating said control device upon 55 adjustment of a selected one of said devices to a fixed reference point.

2. In combination with the adjustable tuning device of a radio receiver, a supplemental tuning device, a rotatable station selector disc arranged 60 to vary said tuning device to different station reception positions, a plurality of independent finger positioning devices mechanically associated with said disc, and means, relatively fixed with respect to said rotatable disc for stopping the rotation of said disc upon adjustment of a selected one of said devices to a fixed reference point, said stopping means comprising an element arranged to rock between a pair of stop members and means cooperating with the ele- 65

ment at its rocking limits to control said supplemental device.

3. In combination with the adjustable tuning device of a radio receiver, a supplemental tuning device, a rotatable station selector disc arranged 5 to vary said tuning device to different station reception positions, a plurality of independent finger positioning devices mechanically associated with said disc, and means, relatively fixed with respect to said rotatable disc for stopping 10 the rotation of said disc upon adjustment of a selected one of said devices to a fixed reference point, said stopping means including a member arranged to rock between a pair of limiting points, means cooperating with said member at 15 its rocking limits to control said supplemental device, and means mechanically associated with each of said independent devices for rocking said member.

4. In combination with the adjustable tuning 20 device of a radio receiver, a supplemental tuning device, a rotatable station selector disc arranged to vary said tuning device to different station reception positions, a plurality of independent finger positioning devices mechanically associated with said disc, and means, relatively fixed with respect to said rotatable disc for stopping 25 the rotation of said disc upon adjustment of a selected one of said devices to a fixed reference point, said stopping means being constructed and 30 arranged to shift between a pair of limiting positions in accordance with the direction of rotation of said disc and means cooperating with said stopping means at its shifting limits to control 35 said supplemental device.

5. In combination with the adjustable tuning device of a radio receiver, a fine tuning mechanism, a rotatable station selector disc arranged to vary said tuning device to different station reception positions, means controlling the effect 40 of said mechanism, a plurality of independent finger positioning devices mechanically associated with said disc, and means, relatively fixed with respect to said rotatable disc for stopping 45 the rotation of said disc upon adjustment of a selected one of said devices to a fixed reference point, each of said positioning devices comprising a depressible button carrier member, and each 50 depressible button being provided with a pin adapted to contact said stopping means to actuate said controlling means.

6. In combination with the adjustable tuning device of a radio receiver, a rotatable station selector disc arranged to vary said tuning device to different station reception positions, a plurality of independent finger positioning devices mechanically associated with said disc, each of said 55 devices comprising a member provided with a bore, a spring-biased button means in each bore, and means, relatively fixed with respect to said 60 rotatable disc for stopping the rotation of said disc upon adjustment of a selected one of said devices to a fixed reference point, each of said 65 independent devices including means for adjusting a device to any desired position on the disc for calibration thereof, a pin carried by each 70 of said button means, and each button means being responsive to pressure of a finger for projecting a pin from a positioning device in such a manner that a pin comes in contact with the stopping 75 means.

7. In combination with the adjustable tuning device of a radio receiver, a signal-responsive control circuit, a rotatable station selector disc arranged to vary said tuning device to different 75

- station reception positions, a plurality of independent finger positioning devices mechanically associated with said disc, and means, relatively fixed with respect to said rotatable disc for stopping the rotation of said disc upon adjustment of a selected one of said devices to a fixed reference point, each of said positioning devices being provided with a bore to receive the finger of the user, and said stopping means including a shiftable element adapted to be adjusted between a pair of limiting positions, said shiftable element being included in a switch device for controlling the operation of said control circuit, and the path of rotation of said disc being such that the user's finger comes into contact with said shiftable element.
8. In combination with the adjustable tuning device of a radio receiver, a fine tuning device, means for controlling the operation of the latter, a rotatable station selector disc arranged to vary said tuning device to different station reception positions, said disc being provided with a plurality of independent finger positioning devices, and means, relatively fixed with respect to said rotatable disc, for stopping the rotation of said disc and actuating said controlling means upon adjustment of a selected one of said devices to a fixed reference point corresponding to the position of said stopping means.
9. In combination with the adjustable tuning device of a radio receiver, a supplemental tuning device, a rotatable station selector disc arranged to vary said tuning device to different station reception positions, said disc being provided with a plurality of independent finger positioning devices, and means, relatively fixed with respect to said rotatable disc for stopping the rotation of said disc upon adjustment of a selected one of said devices to a fixed reference point corresponding to the position of said stopping means, each of said finger positioning devices comprising an aperture provided in the disc and said stopping means comprising an adjustable element constructed and arranged to be rocked between a pair of limiting positions and means cooperating with the element at its rocking limits to control said supplemental device.
10. In combination with the adjustable tuning device of a radio receiver, a circuit for controlling signal reception, a rotatable station selector disc arranged to vary said tuning device to different station reception positions, said disc being provided with a plurality of independent finger positioning devices, and means, relatively fixed with respect to said rotatable disc for stopping the rotation of said disc upon adjustment of a selected one of said devices to a fixed reference point corresponding to the position of said stopping means, said stopping means being included as a control switch in said controlling circuit, and an additional stopping means arranged adjacent said disc at a point diametrically opposite the position of the first stopping means, both said stopping means being positioned in such a manner with respect to said positioning devices that a finger disposed in a device comes into contact with either of said stopping means when the disc is rotated.
11. In combination with a radio receiver of the superheterodyne type, automatic frequency control means, responsive to received signal energy, for adjusting the local oscillator frequency to a magnitude such that the frequency of the intermediate frequency energy is made to approach an operating frequency value, a mechanism for rendering the frequency control inoperative, an adjustable station selector constructed and arranged to vary the position of the adjustable tuning device of the receiver, said selector being provided with a plurality of independent finger positioning devices for adjusting the selector to different desired station settings, and said mechanism being so constructed and arranged with respect to said selector that the mechanism is actuated when a positioning device is adjusted to a predetermined reference point.
12. In combination with a radio receiver of the superheterodyne type, automatic frequency control means, responsive to received signal energy, for adjusting the local oscillator frequency to a magnitude such that the frequency of the intermediate frequency energy is made to approach an operating frequency value, switch means for rendering the frequency control inoperative, an adjustable station selector constructed and arranged to vary the position of the adjustable tuning device of the receiver, said selector device being provided with a plurality of independent finger positioning devices for adjusting the selector to different desired station settings, and said switch means being positioned in the path of movement of said devices in such a manner that the switch is actuated when a device is adjusted to a predetermined reference point, and additional means for rendering said switch inactive to affect the frequency control upon removal of the finger from the selected device.
13. In combination with a radio receiver of the superheterodyne type, automatic frequency control means, responsive to received signal energy, for adjusting the local oscillator frequency to a magnitude such that the frequency of the intermediate frequency energy is made to approach an operating frequency value, switch means for rendering the frequency control inoperative, an adjustable station selector constructed and arranged to vary the position of the adjustable tuning device of the receiver, said selector being provided with a plurality of independent finger positioning devices for adjusting the selector to different desired station settings, and said switch means being mechanically associated with said devices in such a manner that the switch is actuated when a device is adjusted to a predetermined reference point, said selector comprising a rotatable dial, and said independent devices comprising adjustable buttons, each button having a pin adapted to be moved into contact with said switch.
14. In combination with a radio receiver of the superheterodyne type, automatic frequency control means, responsive to received signal energy, for adjusting the local oscillator frequency to a magnitude such that the frequency of the intermediate frequency energy is made to approach an operating frequency value, switch means for rendering the frequency control inoperative, an adjustable station selector constructed and arranged to vary the position of the adjustable tuning device of the receiver, said selector being provided with a plurality of independent finger positioning devices for adjusting the selector to different desired station settings, and said switch means being mechanically associated with said devices in such a manner that the switch is actuated when a device is adjusted to a predetermined reference point, an adjustable element adapted to be varied in position between a pair of limiting points, said adjustable element being arranged to actuate said

- switch means at each of said limiting points, said adjustable element being mechanically associated with said independent devices in such a manner that the adjustable element is actuated 5 upon adjustment of a device to a point adjacent said adjustable element.
15. In a superheterodyne receiver provided with at least a first detector adapted to produce intermediate frequency energy of a predetermined operating intermediate frequency, means 10 for rectifying the intermediate frequency energy and a local oscillator adapted to impress locally produced oscillations upon said first detector, an adjustable tuning device electrically associated 15 with said first detector and oscillator, means, responsive to a variation of frequency of said intermediate frequency energy from the operating frequency, for adjusting the oscillator frequency in a sense to cause said intermediate frequency energy to approach said operating frequency, a switch device for controlling the operation of said oscillator frequency control means, means for varying said adjustable tuning device to predetermined positions, and additional 25 means for actuating said switch device to render the frequency control means inoperative solely at said predetermined adjusted positions of the tuning device.
16. In a superheterodyne receiver provided 30 with at least a first detector adapted to produce intermediate frequency energy of a predetermined operating intermediate frequency, means for rectifying the intermediate frequency energy and a local oscillator adapted to impress locally 35 produced oscillations upon said first detector, an adjustable tuning device electrically associated with said first detector and oscillator, means, responsive to a variation of frequency of said intermediate frequency energy from the operating 40 frequency, for adjusting the oscillator frequency in a sense to cause said intermediate frequency energy to approach said operating frequency, a switch device for controlling the operation of said oscillator frequency control means, means 45 for varying said adjustable tuning device to predetermined positions, and additional means for actuating said switch device to render the frequency control means inoperative solely at said predetermined adjusted positions of the tuning 50 device, signal amplification reduction means, responsive to rectified intermediate frequency energy, for automatically maintaining the signal amplitude substantially uniform at the said rectifier when the received signal amplitude increases, 55 and said frequency control means acting to cause said intermediate frequency energy to be supplied to said signal rectifier between said tuning device positions whereby the tuning operation between said positions is quiet.
- 60 17. In a radio receiver of the type comprising a main tuning device and a supplemental signal-actuated tuning mechanism for securing accurate tuning at selected station positions of the main device, means for controlling the operation of the supplemental mechanism, an adjustable station selector constructed and arranged to adjust said main device to selected positions, said selector being provided with a plurality of independent station representation devices for positioning an index element, and means constructed and arranged simultaneously to stop the adjustment of said selector upon adjustment of the positioned index element to a fixed reference point corresponding to the position of said stopping means and to actuate said control means.
18. In a radio receiver of the type provided with a station selecting circuit including a main tuning element, an automatic tuning control arrangement for insuring accurate tuning of the receiver at selected positions of the main element, means for rendering said automatic control ineffective, and additional means, responsive to adjustment of said main tuning element, for actuating said last means at said selected positions. 5
19. Selective adjusting mechanism for tuning 10 radio receivers embodying an automatic frequency control circuit comprising a manually shiftable element drivingly connected with a tunable element of said receiver and selectively operable means for stopping the means of the shiftable element when the same and said tunable element reach a desired tuned position, and means operatively associated with said stop means for grounding said automatic frequency control circuit momentarily as said desired tuned 15 position is reached. 20
20. Selective adjusting mechanism comprising rotatable means including a portion formed with a series of openings adapted to receive the finger of an operator when turning the rotatable means, 25 stop means for each opening including a button portion extending in an opening and depressible therein by the finger of the operator, said stop means being normally inactive but being adapted upon depression of the corresponding button in 30 its opening to stop rotation of the rotatable means when the same reaches an adjusted position determined by said stop. 35
21. Selective adjusting mechanism comprising a manually shiftable element and selective means operable during and as a part of the shifting of said element to stop the same when a desired adjusted position is reached, said selective means comprising a plurality of selectors individually 40 and selectively depressible on said manually shiftable element, each depressible selector comprising a button member and a stem-like stop element axially movable on the manually shiftable element, resilient means arranged in contact with said button member and applying pressure 45 directly thereto thereby normally urging said stop element toward inactive position on the shiftable element, and means forming a cooperating stop adapted to engage said stop element when the selector is depressed on said shiftable 50 element whereby to stop the shiftable element in a position determined by said stop element. 55
22. Selective adjusting mechanism comprising rotatable means including a portion formed with openings whereby said means may be grasped in 60 turning the same, means extending in said openings and forming stops selectively operable in effecting turning movement to check said movement when said rotatable means reaches a desired adjusted position determined by the selected stop. 65
23. In combination with the adjustable tuning condenser of a radio receiver, a rotatable station selector member arranged to actuate said condenser to different station reception positions, a plurality of selectively operable push-buttons mechanically associated with said selector member, means relatively fixed with respect to said rotatable selector member for stopping the rotation of said member upon adjustment of a selected one of said push-buttons to a fixed 70 reference point, a control circuit included in said receiver and having a normally open switch, and means controlled by said push-buttons at their limits of travel for actuating the switch to closed position. 75

24. In combination, an adjustable tuning condenser of a radio receiver, a rotatable station selector member arranged to adjust said condenser to different station reception positions, a plurality of selectively operable push-buttons carried by said selector member and capable of sliding movement in a direction normal to the direction of rotation of the selector member, a stop pin carried by each push-button, means co-operating with the stop pin of an operated push-

button to arrest the motion of the selector member at a desired tuning position upon actuation of a push-button and the simultaneous rotation of the selector member, a control circuit included in said receiver and having a normally open switch, and means controlled by said stop pin at its limit of travel to actuate the switch to closed position. 5

DUDLEY E. FOSTER. 10
